UNITED STATES PATENT OFFICE.

JADWIGA KUCZYNNSKA, OF HOOVERSVILLE, PENNSYLVANIA.

COIN-BANK.

1,245,470.

Specification of Letters Patent.

Patented Nov. 6, 1917.

Application filed May 25, 1917. Serial No. 171,048.

To all whom it may concern:

Be it known that I, JADWIGA KUCZYNNSKA, a citizen of the United States, residing at Hooversville, in the county of Somerset and State of Pennsylvania, have invented certain new and useful Improvements in Coin-Banks, of which the following is a specification.

This invention relates to certain new and useful improvements in coin banks.

The primary object of the invention is the provision of a device adapted for the reception of adjusted coins of uniform denominations, and an automatic lock releasing device being provided for permitting the ready opening of the bank when filled with coins.

A further object of the device is to provide a coin holder having a removable portion permitting the withdrawing of the coins from the bank when the latter is completely filled therewith, it being normally impossible to open the device by a person unfamiliar with its structure.

A still further object of the device is to provide a bank that is easy and inexpensive to manufacture, the same being light in weight as well as fire proof, the same being capable of holding a different number of coins of a given denomination, the amount of money within the bank at any time being readily determined at a glance.

In the drawing forming a part of this application and in which like numerals refer to corresponding parts throughout the several views:

Figure 1 is a side elevation of the device.

Fig. 2 is a central longitudinal sectional view thereof with only a few coins arranged therein.

Fig. 3 is a view of the same partly in elevation and partly in longitudinal section, the bank being substantially filled with coins and having a slightly modified form of bottom structure.

Fig. 4 is a top plan view of the device.

Fig. 5 is a transverse sectional view of the same.

Fig. 6 is a view of the upper portion of the device similar to that shown in Fig. 3 showing the bank partially open.

Fig. 7 is a plan view of the follower employed in the form of the device shown in Fig. 3, and,

Fig. 8 is a transverse sectional view upon line VIII—VIII of Fig. 2.

Referring more in detail to the drawing, it will be noted that the bank comprises a tubular receiver 10 having its internal dimensions of suitable diameter to accommodate coins 11 of the desired dimension which will deposit therein through a side slot 12 adjacent the upper end of the receiver upon which end a closure cap 13 is normally seated.

A false bottom or follower 14 in the form of a disk is arranged within the receiver 10 being supported by means of a spring 15 parallel with the bottom 16 of the receiver, thereby resiliently mounting coin 11. An arm 17 radially extends inwardly of the receiver 10 at a point above the slot 12 and is provided with a semicircular notch 18 in its free end for the reception of a screw 19 threaded into a sleeve 20 which is centrally journaled through the top 21 of the cap 13 and is provided with a head 22 lying outwardly of the cap and arranged with a kerf 23 adapted for the reception of a turning instrument, (not shown).

A head 24 is provided at the lower end of the screw 19 engaging beneath the arm 17 and whereby a turning of the sleeve 20 by means of its head 22 will tighten the cap 13 upon the receiver 10 when the screw 19 is restrained from turning in any suitable manner such as by the insertion of a blade through the slot 12 for engaging the lower roughened face 25 of the head 24. A person unfamiliar with this manner of securing the cover 13 in position such as a child in possession of the bank will be unaware of any manner by which the cap 13 may be removed excepting by completely filling the receiver 10 with the coins 11 until the coins fill the receiver to a point in alinement with the slot 12 with the uppermost coin contacting the face 25 of the screw head 24, and at such times the spring 15 will press the uppermost coin against the face 25 with sufficient pressure to prevent the turning of the screw 19 when the sleeve 20 is turned by means of its head 22 in the proper direction to release and elevate the cap 12 as best illustrated in Fig. 6 of the drawing.

It will be understood that when the receiver 10 is nearly filled with the coins 11 to a point adjacent the slot 12, that additional coins may be inserted by slightly depressing all of the inclosed coins by means of the incoming coins, such depression being rendered possible by action of the spring 15.

Perforations 26 are provided through the side of the receiver 10 for determining the height that the coins have attained within the receiver above the false bottom 14 thereof which is normally in alinement with an annular shoulder 27 of the receiver, numerals 28 being supplied upon the receiver denoting the value of the coins when reaching different elevations within the receiver.

10 A central opening 29 may be provided in the false bottom 14 and a similar opening 30 in the bottom 16 of the receiver while the last named opening will normally be filled with a suitable sealing means 31 such as wax. In this construction, when the device is being employed for receiving coins, the seal 31 will be arranged in place, but when the receiver has been emptied an instrument may be placed through the openings 20 and 29 for engaging the face 25 of the head 24 for retaining the screw 19 stationary and permitting the frame to be secured to the cap 13 upon the receiver.

25 A serviceable bank for children is arranged in which coins may be easily placed and the amount of money within the bank determined at any time while the child will be unable to remove the coins until the receiver 10 is filled therewith. It will be understood that when the cap 13 is released and elevated to the position as illustrated in Fig. 6 the screw 19 may be readily detached from the arm 17 while the coins 11

may be depressed sufficiently to permit the upper coins being removed while the remaining coins may then be readily removed or poured from the device.

35 What I claim as new is:—

40 A device of the class described comprising a receiver having a shoulder spaced from the bottom thereof, a spring within the receiver seated upon the bottom of the latter, a disk mounted upon the said spring normally in substantially the same plane as the said shoulder and adapted for the reception of coins thereon, the said receiver having a coin receiving slot in the side thereof, a radially extending arm within the receiver above the said slot having a notch in its free end, a closure cap normally seated upon the open end of the receiver, an internally threaded sleeve axially journaled through the said cap having a positioning head exteriorly of the cap provided with a kerf, a retaining screw adjustably threaded within the said sleeve with a portion of the screw arranged within the said notch and having a head engaging beneath the said arm, the inner end of said head being roughened and positioned outwardly of the plane of said slot with the uppermost coin in restraining engagement therewith when the receiver is in its filled condition.

45 50 55 60 65

In testimony whereof I affix my signature.

JADWIGA KUCZYNsKA.

Copies of this patent may be obtained for five cents each, by addressing the "Commissioner of Patents, Washington, D. C."
